Cadmon & Co.

UNITED STATES PATENT OFFICE.

ZACHARIAS W. SHIELDS, OF HARRINGTON, WASHINGTON.

WASHING-MACHINE.

SPECIFICATION forming part of Letters Patent No. 451,530, dated May 5, 1891.

Application filed October 28, 1890. Serial No. 369,603. (No model.)

To all whom it may concern:

Be it known that I, ZACHARIAS W. SHIELDS, a citizen of the United States, residing at Harrington, in the county of Lincoln and 5 State of Washington, have invented a new and useful Washing-Machine, of which the following is a specification.

The invention relates to improvements in washing-machines.

10 The object of the present invention is to simplify and improve the construction of the reciprocating rubber washing-machine and to enable the operation of washing to be performed at the expenditure of comparatively 15 little exertion on the part of the operator.

The invention consists in the construction and novel combination and arrangement of parts hereinafter fully described, illustrated in the accompanying drawings, and pointed 20 out in the claim hereto appended.

In the drawings, Figure 1 is a perspective view of a washing-machine constructed in accordance with this invention. Fig. 2 is a vertical longitudinal sectional view. Fig. 3 is a 25 similar view taken on the line $\alpha\alpha$ of Fig. 2.

Referring to the accompanying drawings, 1 designates a washing-machine body or tub which is approximately T-shaped, and which is supported by legs 2, connected by cross- 30 bars 3 and 4. The cross-bars 3 have pivot-

ally connected to them the lower ends of oscillating bars 5, which have their upper ends similarly connected with a vibrating or reciprocating rubber-frame 6, carrying a pivoted 35 rubber 7, which acts in conjunction with a stationary hinged rubber 8, arranged transversely of the longitudinal portion 9 of the body or tub and extending to the end of the side portion or lateral extension 11. The vi- 40

brating frame consists of a handle-bar 12, to which the oscillating bars 5 are pivoted, and parallel bars 13, which are provided intermediate of their ends with depending arms 14, and have their ends at one side of the tub 45

connected by the handle-bar 12, and their other ends are connected by a rod 15. The rubber 7 is pivoted between the depending arms 14 of the vibrating frame 6, and consists of a pair of rollers 16, journaled in side 50

pieces 17, which have their ends connected by end cross-pieces 18, which form with the

side pieces 17 a rubber-frame. The stationary rubber consists of horizontal bars 19 and transverse slats 20, which are secured to the upper faces of the bars, and the said rubber 55 8 is provided at one end with a cross-piece 21, which is pivoted between the sides of the lateral extension 11 of the body or tub, and the free end has attached to it one end of a rope 22, which passes over a pulley 23 and 60 has its other end attached to a lever 24. The pulley 23 is journaled in a suitable bracket mounted upon the upper edge of the board, and the lever 24 has one end pivoted to one of the legs 2, and its other end is provided 65 with an adjustable weight 25, by means of which the pressure exerted by the stationary hinged rubber against the vibrating rubber can be regulated. The end of the tub or body 70 adjacent to the side of the stationary rubber is provided with an inclined board 26, which affords convenient means for attaching a wringer and to hold various articles needed during the operation of washing.

The oscillating bars are arranged upon opposite sides of the lateral extension or side portion of the body or tub, and are in no manner inconvenient to or in the way of persons operating the machine, and in use they do not pass beyond the body of the tub. 80

What I claim is—

In a washing-machine, the combination of the body, the pulley mounted thereon, the stationary rubber having one end hinged and arranged within the body, the lever pivoted 85 at one end, the weight adjustably mounted on the lever and adapted to vary the pressure, the rope passing over the pulley and having one end attached to the stationary rubber and the other end connected with the lever, the 90 oscillating bars, and the vibrating frame provided with a pivoted rubber and being pivotally connected to the upper ends of the oscillating bars, substantially as described.

In testimony that I claim the foregoing as 95 my own I have hereto affixed my signature in presence of two witnesses.

ZACHARIAS W. SHIELDS.
